UNITED STATES PATENT OFFICE

150,034

DESIGN FOR A PAPER BOX BODY

William E. Selby, Jr., South Orange, N. J., assignor to Dillon-Beck Manufacturing Company, Irvington, N. J., a corporation of New Jersey

Application May 16, 1946, Serial No. 129,742

Term of patent 3½ years

(Cl. D34—15)

To all whom it may concern:

Be it known that I, William E. Selby, Jr., a citizen of the United States, residing at South Orange, in the county of Essex and State of New Jersey, have invented a new, original, and ornamental Design for Paper Box Body, of which the following is a specification, reference being had to the accompanying drawings, forming a part thereof.

In said drawings:

Fig. 1 is a perspective view of the paper box body embodying my new design as viewed from the front and one end, with sides thereof dropped to lie in the plane of the box bottom;

Fig. 2 is a perspective view of the paper box body as viewed from the rear and opposite end, with sides thereof dropped to lie in the plane of the box bottom; and

Fig. 3 is a perspective view of the paper box body as positioned in Fig. 2, but with the dropped sides thereof erected in upstanding relation to the box bottom.

I claim:

The ornamental design for a paper box body, as shown and described.

WILLIAM E. SELBY, JR.
